2 SHEETS—SHEET 2.

Inventor:
Thomas P. Briody,

By Chas. E. Riordon

Atty.

UNITED STATES PATENT OFFICE.

THOMAS P. BRIODY, OF BETHLEHEM, PENNSYLVANIA.

MUSIC-LEAF TURNER.

Application filed November 22, 1921. Serial No. 516,913.

To all whom it may concern:

Be it known that I, THOMAS P. BRIODY, a citizen of the United States, and a resident of Bethlehem, in the county of Northampton and State of Pennsylvania, have invented certain new and useful Improvements in Music-Leaf Turners, of which the following is a specification.

My invention relates to leaf-turners and has for its object the provision of an inexpensive mechanism of novel construction, arrangement and operation by the use of which the leaves of a musical composition may be turned successively without interrupting the performance. Another object of the invention is to provide novel means for securing a book or a multiple-sheet composition in position upon a piano desk or a music stand, and another object of the invention is to provide novel means for effecting simultaneous return of all the sheets to the initial position. The invention also provides means for supporting and turning the single sheet of a two-page composition, and also provides means whereby sheets or books of different heights may be accommodated upon the same desk or stand.

In the annexed drawings, which illustrate one embodiment of my invention, Fig. 1 is a front elevation of a piano desk having my improved leaf-turner applied thereto with parts in section.

Fig. 2 is a rear elevation with parts in section.

Fig. 3 is a transverse section on the line 3—3 of Fig. 2.

Fig. 4 is a section on the line 4—4 of Fig. 2.

Fig. 5 is a view partly in elevation and partly in section, taken approximately in the same plane as Fig. 3 but looking in the opposite direction.

Figure 6 is a view similar to Fig. 5, showing a sheet midway the limits of its turning movement.

Fig. 7 is a detail showing the arrangement for supporting and turning a single loose sheet.

In the drawings, the reference numeral 1 indicates a piano desk which is preferably in the form of a casing adapted to house the working parts as will be readily understood upon reference, more particularly, to Figs. 2, 3 and 4, the back wall of the casing being omitted in Fig. 2. The desk is provided with the usual ledge or shelf 2 at its bottom

upon which the sheet or book may rest, and it is provided in its front wall with openings or sockets 3 which are equidistant from its bottom. In the top edge of the desk are 60 sockets 4 arranged in vertical alinement with the respective sockets 3 and normally receiving pins 5 carried by a rail 6. Ordinarily, the rail 6 serves as a cap to impart an attractive finish to the top of the desk but 65 if the pages of the composition to be played are of less height than the distance between the shelf or rest 2 and the turning arms, the rail 6 is removed from the top of the desk and fitted to the front thereof by having its 70 pins 5 engaged in the sockets 3. The rail will then serve as a rest or support for the music, and it will be understood that a series of sockets 3 may be provided.

In the front wall of the desk, near the top and sides thereof, I provide openings or horizontal slots 7 and extending from end to end of these slots are pins 8 which constitute fulcrums or pivots for clamping plates 9 which depend from the respective pivots 80 in front of the desk and are adapted to engage over the book covers or the outside sheets of the composition and clamp them to the desk. The clamping plates are extended within the desk beyond their respective pivots, as shown at 10, the extensions being connected by a coupling rod 11. A link 12 is connected to the rod 11 and depends therefrom to a point near the bottom of the desk where it is pivoted to a lever 13 90 which is fulcrumed at the bottom of the desk and projects through a slot in the end wall thereof. A leaf spring 15 is secured within the desk above each extension or arm 10 and bears upon the extension to hold it 95 against free movement but permit movement under the influence of the lever 13. A larger stronger leaf spring 16 is secured upon the front of the desk and bears upon the clamping plate 9 to hold it firmly 100 against the desk or against the sheet or cover interposed between it and the desk.

Upon the front of the desk, near the top and centrally thereof, is a bracket 17 carrying a pin or stud 18 on which the inner 105 ends of the carrying arms 19 are pivotally engaged. Upon each carrying arm, at the free end thereof, is a clasp or clip 20 which may be of any approved form and is adapted to engage the free upper corner of one 110 sheet or leaf and secure the same. Above the carrying arms are a plurality of turning

bars or rods 21 each of which is connected to one of the carrying arms whereby movement of the bar or rod will effect swinging of the arm and turning of the music sheet. 5 The connections between the turning bars and the carrying arms may be of any preferred form and I have illustrated a cheap and simple expedient consisting in forming a loop 22 in the arm which is carried up 10 to and around the respective bar or rod. The inner ends of the turning bars or rods are turned upward and journaled in a supplemental casing or box 23 secured upon the front of the desk above the bracket 17, and 15 upon the upturned end or journal 24 of each turning rod is secured a double cam 25. The cam 25 is constructed with the opposed cam faces 26 which converge from the upper end of the cam body to the lower end thereof 20 as shown most clearly in Figs. 5 and 6. Arranged within the desk side by side and aligned with the respective cams are plungers 27 each provided at its upper end with a lateral finger 28 which is arranged to oper- 25 atively engage the cam faces 26 of the respectively adjacent cam. The plungers are yieldingly held normally in a raised position by coiled springs 29 disposed between the lower ends of the plungers and a rest 30 bar 30 within the desk. Plunger rods 31 depend from the plungers and pass through guiding passages 32 in the rest bar 30, links 33 connecting the piston rods with key levers 34 which are fulcrumed within a cas- 35 ing 35 carried by the bottom of the desk and constructed with notches or slots in which the key levers play and by which they are guided.

Within the desk, at the top of the same 40 and extending across the upper ends of the plungers, is a presser lever 37 fulcrumed at one end and having a link 38 pivoted to and depending from its free end, the lower end of said link being pivoted to a finger lever 39 which is fulcrumed at the desk and projects through a slot 40^a in the end wall of the same, the lever 39 being arranged re- 45 versely to the lever 13 as clearly shown in Fig. 2.

50 The center of the turning movement of the leaves or sheets is, of course, the line along which they are bound or joined together and the several carrying arms 19 are mounted upon a common pivot, but to 55 avoid bulkiness the fulcrums of the turning bars are arranged side by side and the bars at the sides of the center swing eccentrically to the respective carrying arms. To accommodate the varying angular relation of the turning bar and the carrying arm, 60 the loop 22 and the clip 20 are slidably engaged with the turning bar. When a single sheet is to be held and turned, the central turning bar and carrying arm are utilized 65 and two clips 20^a and 20^b are employed, as

shown in Fig. 7. The clip 20^a is engaged with the upper edge of the sheet near one corner of the same and then slid along the arm and bar inwardly until it strikes the stop shoulder or abutment 40 on the arm, 70 the edge of the sheet being held by one hand so that it will be kept flat or straight. When the clip 20^a impinges upon the abutment 40, the outer corner of the sheet is engaged in the clip 20^b to be held thereby, the operation 75 of turning the sheet being identical with the turning of the leaves of a book.

When the device is to be used the lever 39 is depressed, which action throws the turning bars or rods 21 to a central position at 80 substantially right angles to the case. The lever is then pressed rearwardly into the deeper slot 41 and is locked in this position against the shoulder 42. The lever 13 is then depressed thereby pulling downwardly 85 upon the extensions or arms 10 of the clamping plates 9 and rocking said plates upwardly and outwardly from the desk. The upper outer corners of the book covers or of the outside sheets are then engaged under 90 the clamping plates after which the lever 13 is released and the springs 15 and 16 will cause the clamping plates to bear upon and firmly hold the book or the outside leaves. The lever 39 is then released and the remain- 95 ing leaves or sheets are then engaged in the clips 20 in an obvious manner whereupon the device will be ready for use. When the first sheet is to be turned, the key lever 34 at the left hand end of the series of key levers is 100 depressed so that the plunger connected therewith will be drawn downwardly and the finger 28 on said plunger will be caused to ride downwardly on the adjacent cam face 105 26 so that the cam body will be rotated and the turning bar connected therewith swung sharply from the right side of the desk to the left side thereof. The carrying arm connected with the turning bar will, of course, follow the movement and the first sheet will 110 be turned, the spring 29 raising the plunger to its normal position and carrying the finger out of the way of the following cam face 26. It will be understood that the key 115 lever is depressed with a sharp quick blow so that while the lever will be almost instantaneously released, the momentum acquired by the cam and turning arm will carry them through half a revolution and bring the mating cam face under the finger. The operation 120 is repeated for each succeeding leaf by depressing the key levers successively, and it will be understood that any desired number of key levers and associate parts may be provided but ordinarily three will be sufficient as an eight-page composition will be 125 thereby accommodated. If, after a leaf has been turned, the same key lever be depressed, the finger 28 will be caused to ride upon the cam face mating with the face 130

upon which it previously rode so that a reverse movement will be imparted to the turning bar. To effect the reverse movement of all the bars simultaneously at the 5 end of the performance, the lever 39 is depressed so that a pull is exerted through the link 38 to draw the presser lever 37 downwardly, and, as this lever 37 is in contact with the upper ends of all the plungers, all 10 the plungers will be forced downwardly and the lateral fingers riding upon the cams 26 will effect the desired turning movement.

From the foregoing description, taken in connection with the accompanying drawings, it will be seen that I have provided a simple and compact mechanism whereby the leaves of a musical composition may be readily turned during rendition of the music without interrupting the performance. 15

Having thus described my invention, what I claim as new and desire to secure by Letters Patent of the United States is:

1. The combination with a music desk having spaced sockets in its front side and in 25 its upper edge, of a cap rail having spaced pins projecting from one side to engage the sockets in the upper edge of the desk or the sockets in the front side thereof.

2. The combination with a music desk, of 30 a plurality of carrying arms pivoted concentrically upon the desk, means on said arms to secure sheets of music, a plurality of turning bars above the carrying arms having journals disposed side by side upon 35 the desk, slideable connections between the turning bars and the respective carrying arms, and means upon the rear of the desk and acting on the journals of the turning bars to swing the same.

3. The combination with a music desk, of 40 a plurality of carrying arms pivoted concentrically upon the desk, means on said

arms to secure sheets of music, a plurality of turning bars above the carrying arms having journals disposed side by side upon 45 the desk, slideable connections between the turning bars and the respective carrying arms, mating downwardly converging cam faces on the journals, fingers disposed laterally with respect to the journals and arranged to ride on said cam faces, and means for reciprocating the fingers. 50

4. The combination with a music desk, of a plurality of carrying arms pivoted concentrically upon the desk, means on said 55 arms to secure sheets of music, a plurality of turning bars above the carrying arms having journals disposed side by side upon the desk, slideable connections between the turning bars and the respective carrying 60 arms, mating downwardly converging cam faces on the journals, fingers disposed laterally with respect to the journals and arranged to ride on said cam faces, plungers carrying said fingers, springs holding said 65 plungers normally elevated, key levers at the bottom of the desk, and operative connections between the key levers and the respective plungers.

5. The combination with a music desk, 70 of a plurality of turning bars mounted on the desk, means for supporting leaves from said bars, means for successively swinging the bars in one direction including a plurality of normally raising vertically movable plungers, a presser lever extending across and bearing upon the upper ends of all the plungers, a finger lever below the presser lever, and a link connecting the finger lever and the presser lever whereby depression of the finger lever will effect simultaneous return of all the turning bars to initial position. 75 80

THOMAS P. BRIODY.
